PAGE 4

Fig. 4

Fig. 5

Fig. 6.

FIG. 1 is a view in side elevation of a chair in accordance with the invention;

FIG. 2 is a view in front elevation thereof;

FIG. 3 is a view in back elevation thereof;

FIG. 4 is a view along section 4—4 of FIG. 1;

FIG. 5 is a view along section 5—5 of FIG. 1; and

FIG. 6 is a front perspective view of the chair with the legs removed for convenience of illustration.

The dominant features of my design reside in those portions shown in full lines on the drawing.

I claim:

The ornamental design for a chair, substantially as shown and described.
